No. 813,797.

PATENTED FEB. 27, 1906.

J. M. HOPKINS.
RAILWAY CAR TRUCK.
APPLICATION FILED JUNE 12, 1905.

UNITED STATES PATENT OFFICE.

JAMES M. HOPKINS, OF CHICAGO, ILLINOIS.

RAILWAY-CAR TRUCK.

No. 813,797.

Specification of Letters Patent.

Patented Feb. 27, 1906.

Application filed June 12, 1905, Serial No. 264,768.

To all whom it may concern:

Be it known that I, JAMES M. HOPKINS, a citizen of the United States, residing in Chicago, county of Cook, and State of Illinois, 5 have invented certain new and useful Improvements in Railway-Car Trucks, of which I do declare the following to be a full, clear, and exact description, reference being had to the accompanying drawings, forming part of this specification.

The present invention has for its main object to provide a combined truck-bolster and spring-support. The invention also is designed to provide various other features of improvement, all of which will be hereinafter described, and particularly pointed out in the claims at the end of this specification.

Figure 1 is a view in vertical longitudinal section through half of a car-truck embodying my invention. Fig. 2 is an end view of the combined truck-bolster and spring-support, the end of the body-bolster and portions of the side frame being also shown, certain parts being broken away for better illustration. Fig. 3 is a perspective view of the end portion of my combined truck-bolster and spring-support. Fig. 4 is a detail perspective view of one of the spring-caps or side bearings.

30 The body-bolster A of the truck may be of any suitable construction. As shown, this body-bolster is provided centrally with a depending center bearing-post a, adapted to enter a corresponding centrally-disposed socket b of the combined truck-bolster and spring-support B. This combined truck-bolster and spring-support B is formed of metal, and inasmuch as each of its end portions will be of the same construction I have not deemed it necessary to illustrate both ends of the combined truck-bolster and spring-support in the drawings. Preferably the combined bolster and spring-support B is of channeled or trough-like shape, the bottom bars b' of each 45 end being sufficiently depressed to form a support for the coil-springs C. Upon the group of springs C at each end of the truck-bolster rests a side bearing or spring-cap D, the ends d of which project laterally into seats or guide- 50 ways b², that are formed in the side walls b³ of the combined truck-bolster and spring-support. The ends of the body-bolster A may be supported in any convenient manner upon the side bearings or spring-caps D; but as shown 55 the upper face of each side bearing or spring-cap D is formed with a groove d' to receive

the bearing-balls E, that enter a corresponding groove a', formed adjacent the end of the body-bolster A and upon its under side. The groove d' in the side bearing of spring-cap D and preferably also the groove a' will be formed deeper about the center than adjacent the ends, thus having a tendency to restore the body-bolster A to a normal central position.

60 Above and below the ends of the combined truck-bolster and spring-support B extend, respectively, the trussed bars F and G of the side frame, and these bars sit within seats or depressions b⁴ and b⁵, that are formed at the top and bottom, respectively, of the combined truck-bolster and spring-support. Through the bars F and G and also through the laterally-extending parts b⁶ and b⁷ of the seats b⁴ and b⁵ pass the through-bolts H, that 70 pass also through the side frame-bars F and G and securely hold the parts in position.

75 From the foregoing description it will be seen that by the employment of my improved truck-bolster and spring-support the necessity of providing a separate spring-plank is avoided. It will also be seen that the side bearings or spring-caps D, resting upon the springs C, serve to carry practically all the weight of the car on the springs and 80 the central portion of the truck-bolster while serving as a guide for the center pin that depends from the body-bolster receives comparatively little strain incident to the weight 85 of the car. The advantage in thus transmitting the weight of the car directly upon the side bearings and through them to the springs and side frames will be readily appreciated by those familiar with this class of inventions.

90 It is manifest that the precise details of construction above set out may be varied within wide limits without departure from the spirit of the invention and features of the invention may be employed without its adoption as an entirety.

95 Having thus described my invention, what I claim as new, and desire to secure by Letters Patent, is—

1. A car-truck comprising a combined truck-bolster and spring-support formed integrally and of metal, springs mounted upon said spring-support, and a side bearing mounted upon said springs and provided in its top surface with a bearing-surface to receive the weight of the body-bolster.
2. A car-truck comprising a combined

truck-bolster and spring-support formed integrally and of metal, springs mounted upon said spring-support, a side bearing mounted upon said springs and provided in its top 5 with a grooved bearing-surface to receive the weight of the body-bolster.

3. A car-truck comprising a combined truck-bolster and spring-support, springs mounted upon said spring-support, side bearings mounted upon said springs and provided 10 in their tops with bearing-surfaces, a body-bolster having integral bearing-surfaces extending over the bearing-surfaces of the side bearings, and bearing-balls loosely disposed 15 between said bearing-surfaces.

4. A car-truck comprising a combined truck-bolster and spring-support, springs mounted upon said spring-support, side bearings mounted upon said springs and provided 20 in their tops with grooved bearing-surfaces, a body-bolster having integral grooved bearing-surfaces extending over the bearing-surfaces of the side bearings, and bearing-balls loosely disposed in the grooves in said bearing-surfaces.

5. A car-truck comprising a combined truck-bolster and spring-support, springs mounted upon said spring-support, side bearings mounted upon said springs and provided 25 in their tops with grooved bearing-surfaces, a body-bolster having integral grooved bearing-surfaces.

30

ing-surfaces extending over the bearing-surfaces of the side bearings, the grooves in both said surfaces being formed deeper at their centers than at their ends, and bearing-balls 35 loosely disposed in said grooves.

6. A car-truck comprising a combined truck-bolster and spring-support formed integrally of metal and provided at its center with a socket to receive the center of the 40 truck, springs mounted upon said spring-support, side bearings mounted upon said springs and provided in their tops with grooved bearing-surfaces, body-bolster having integral grooved bearing-surfaces extending over the bearing-surfaces of the side bearings, the grooves in both said surfaces being formed deeper at their centers than at their ends, and bearing-balls loosely disposed in said grooves.

7. The combination with a combined truck-bolster and spring-support formed integral and of metal and provided at its ends with laterally-extended seats to receive the upper and lower truss-bars of the side frames, 45 of bolts passing through said seats and truss-bars to retain said parts in position.

JAMES M. HOPKINS.
